(57) **CLAIM**

The ornamental design for a portable carrier for reusable grocery-style bags, as shown.

DESCRIPTION

FIG. 1 shows a front perspective view of a portable carrier for reusable grocery-style bags showing our new design;
FIG. 2 shows a front perspective view thereof;
FIG. 3 shows a rear perspective view thereof;
FIG. 4 shows a front view thereof;
FIG. 5 shows a rear view thereof;
FIG. 6 shows a left side view thereof;
FIG. 7 shows a right side view thereof;
FIG. 8 shows a top view thereof;
FIG. 9 shows a top view thereof; and,
FIG. 10 shows a bottom view thereof.

The broken line showing of environment in the drawings is included for the purpose of illustrating only and forms no part of the claimed design. The carrier strap is shown broken away to indicate that no particular length is claimed.
